DESIGN FOR A GAME BOARD

Don L. Kreider, Wadsworth, Ohio

Application March 17, 1947, Serial No. 137,672

Term of patent 7 years

(Cl. D34—5)

To all whom it may concern:

Be it known that I, Don L. Kreider, a citizen of the United States, residing at Wadsworth, in the county of Medina and State of Ohio, have invented a new, original, and ornamental Design for a Game Board, of which the following is a specification, reference being had to the accompanying drawing, forming a part thereof.

The figure is a plan view of a game board, embodying my new design.

The game board is of conventional thickness, the design appearing on the top surface only.

I claim:

The ornamental design for a game board, as shown and described.

DON L. KREIDER.
